UNITED STATES PATENT OFFICE.

MAX WILLIAM FEIG AND ULRICH ARNIM FEIG, OF BAD ELSTER, GERMANY.

ARRANGEMENT OF NETTINGS FOR RECLINING AND SITTING FURNITURE.

1,120,187.

Specification of Letters Patent.

Patented Dec. 8, 1914.

Application filed December 1, 1913. Serial No. 804,065.

To all whom it may concern:

Be it known that we, MAX WILLIAM FEIG and ULRICH ARNIM FEIG, both subjects of the German Emperor, and residents of Bad Elster, Germany, have invented certain new and useful Improvements in Arrangements of Nettings for Reclining and Sitting Furniture, of which the following is a specification.

10 The present invention relates to the arrangement of a netting for reclining and sitting furniture, in which the netting having free elastic outside edges is resiliently and adjustably held by aid of pivotally arranged supporting brackets with tension devices.

The invention is particularly characterized in that between the link chains, rope pulley and the like arranged longitudinally to the netting and the tension springs secured to the frame, downward directed supporting brackets are provided, which are coupled to pivotally arranged adjusting brackets on which the tension devices act in such a manner, that by these and by aid of the said brackets each pair of parallel chains with their respective tension springs are kept at a suitable tension.

The invention is further characterized in that the free outside edges are formed by transverse webs provided on the top of the supporting brackets and of closed chain links coupling the same to each other, and that the thus formed edges are connected by arrangements, by means of which the tension, at which the transverse webs of the brackets and the links engage in each other, is accurately regulated. In consequence of such arrangement, it is obtained, that the tension of the netting, when it has slackened by use, is easily restored and may be adjusted for persons of a light or a heavy weight. It is furthermore obtained, that the netting can yield everywhere, also at any part of the outside edges, and as the links are always kept taut against each other, all clattering noise is avoided.

In the accompanying drawings a constructional form of the new arrangement of the netting is exemplified.

Figure 1 is a top view with the frame supporting it. Fig. 2 is a section on the line

A—B in Fig. 1, Fig. 3 is a side view of the rear of a seating furniture, Fig. 4 is a section on the line C—D through Fig. 1, and Figs. 5 and 6 are elevation and plan respectively of the corner bracket arrangement supporting the netting.

In the constructional form shown in the drawing the netting which is formed by the crossing chains *a*, *b* has on three sides a free edge. The netting is held at these edges in an elastic manner by means of helical springs *c*, which on the one hand are secured to the frame *e*, and on the other hand act on brackets *D*. These brackets *D* are pivoted at *D*¹ at the lower ends to the frame *e*, while the central bars are connected to springs *c*, which tend to turn the brackets upward. To these cross bars of the brackets are hinged brackets *f* obliquely inclined upward, which are provided with eye-shaped bends *f*¹ and have cross bars *f*² (see in particular Fig. 4). These cross bars, together with links *g* engaged in the bends *f*¹ form the free edges. The links *g* consist of brackets, the ends *g*¹ forming eyes connected with each other by means of wires *h*. This arrangement allows of an easy assembling. The links *g* are simply engaged in the bends *f*¹ of the brackets and the ends of the links are closed by the wires *h* having at either end a hook shaped bend, so that the links are made to form an integral part.

The links *g* are provided at the ends *g*¹ with inward bends *g*² into which the transversely extending chains *b* are hooked at their two ends, and the longitudinal chains *a* at their one end.

The springs *c* press the brackets upward and out, whereby the chains *a* and *b* are held under tension in known manner. The edges formed by the transverse bars *f*² of the brackets and the links *g* can freely yield and as they consist of members hinged to each other, independently at the various points.

The corner brackets *i* have transverse bars *i*¹ bent to an angle and have ends, which extend downward to each side, and are each by itself coupled by means of links *i*² to a bracket *k* arranged on the respective side (see in particular Figs. 5 and 6). These brackets *k* are pivoted on the adjoining sides of the corner posts and are each independ-

ently under tension of springs c^1 forcing them upward, which act on the links i^2 . The transverse bars i^1 of the corner brackets form the connecting links between two neighboring edges, the end links of which are engaged in bends in the bars i^1 .

The longitudinal edges of the netting are secured at the ends opposite the free edges in any known manner by means of helical 10 springs attached to the frame e . Between the springs l and the end links of the longitudinal edges tension yokes m are provided, which engage a threaded bolt n secured to the end links. By tightening these tension 15 yokes m the bolts n are moved and the springs l are tightened. By the provision of the said tension yokes it is thus obtained, that the parts of the links forming the longitudinal edge can at all times, also when the 20 spring l is released, be so tightened, that they form one taut continuous whole.

The arrangement is particularly suited for detachable upholsterings secured to the outsides of the wooden frame by means of 25 buttons, hooks and the like. All the brackets are coupled to the frame e by means of tension wires c . The longitudinal chains a are held taut at their end by means of helical springs p . These are coupled at one end 30 to the longitudinal chains a by means of links r, s , and at the other end to the frame e by means of staples s^1 . The ends of the links r extend obliquely downward and toward the middle of the frame and are 35 hinged at their extremities to brackets t . The latter are pivoted below to a cross beam or a cross rail u of the frame e (see in particular Fig. 2) and at the top coupled by 40 tension wires v or the like to helical springs w . To these are coupled at their other ends chains x which are secured to hook members y . These members engage with female 45 thread over screw spindles z , which are pivoted in eyes j secured to the frame e . By turning the screw spindle z by aid of its handle, the members y can be displaced in either direction whereby the helical springs w are tightened or slackened. The tightening 50 of these springs, in turn, because of the tension wires v turn the brackets t in the direction of the arrow Fig. 2, whereby the brackets r and with them the netting a, b is at the respective end pressed obliquely upward, and the springs p are simultaneously 55 tightened (see position in Fig. 2 shown by dot and dash lines). By very slightly tightening the spindles z this will allow of severely tightening the netting, thus the tension of the netting can be varied within wide 60 limits, and the netting can be adapted for carrying small or large loads. As shown in the drawing, several such tension gears have been arranged next to each other, and allow of separately tightening the netting 65 in its middle part, where it is subject to the

greatest loads. If necessary such tensioning gears may also be arranged at both ends of the chains.

For obtaining a noiseless connection between the netting and the links g leather 70 backings are provided between the latter and the respective end links of the netting.

We claim:

1. An article of the class described in which the netting having free elastic outside 75 edges is elastically and adjustably held by pressure springs by aid of pivotally arranged supporting brackets having tensioning devices, link chains, ropes or the like of the netting extending longitudinally and 80 held taut by helical springs engaging in cross bars of the supporting brackets having lateral bends, the legs of said brackets movably coupled to brackets on which the tensioning devices act, and adapted to hold 85 each pair of parallel chains with their respective tensile springs by means of said supporting brackets at a uniform tension, the said brackets connected with tension nuts, by means of looped slings, tension 90 springs and link chains, and means for adjustably securing said nuts to the frame.

2. An article of the class described in which the netting having free elastic outside 95 edges is elastically and adjustably held by pressure springs by aid of pivotally arranged supporting brackets, tensioning devices on said brackets said netting having longitudinally extending members, helical springs, brackets which have lateral bands 100 the ends of said brackets movably coupled to supports on which the tensioning devices act, and adapted to hold each pair of longitudinally extending members with their respective tensile springs by means of said 105 supporting brackets at a uniform tension, the said supports connected with tension nuts by means of looped slings, tension springs and longitudinally extending members, said tension nuts screwing on screw 110 spindles and a transverse beam on the frame in which said spindles are secured.

3. A device of the character described in which the netting having free elastic outside 115 edges, is elastically and adjustably held by pressure springs by aid of pivotally arranged supporting brackets, tensioning devices on said brackets, the longitudinally extending members of the netting being held taut by helical springs, brackets which have 120 lateral bends, the ends of said brackets being movably coupled to supports on which the tensioning devices act, and adapted to hold each pair of longitudinally extending members with their respective tensile springs 125 by means of said supporting brackets at a uniform tension, the said supports connected with tension nuts by means of looped slings, tension springs and longitudinally extending members, said tension nuts screwing on 130

- screw spindles secured in the transverse beam of the frame, the edge of the netting formed by cross webs, eye shaped lateral bands of tension shackles and closed links connecting said shackles with each other. 5
4. A device of the character described in which the netting having free elastic outside edges is elastically and adjustably held by pressure springs by aid of pivotally arranged supporting brackets, tensioning devices on said brackets, the longitudinally extending members of the netting being held taut by helical springs, brackets which have lateral bends the ends of said brackets movably coupled to supports on which the tensioning devices act, and adapted to hold the longitudinally extending members with their respective tensile springs by means of said supports at a uniform tension, the said 10 supports connected to tension nuts by means of looped slings, tension springs and longitudinally extending members, said tension nuts screwing on screw spindles a transverse beam of the frame on which spindles are secured, the free edges of the netting formed by cross webs, eye shaped lateral bands of tension shackles and closed links connecting said shackles with each other, the said closed edge links of the netting closed at their upwardly directed legs by means of wire loops and having bends into which the longitudinally extending members forming the netting are immovably engaged with interposed leather packings. 15
5. A device of the character described in which the netting having free elastic outside edges is elastically and adjustably held by pressure springs by aid of pivotally arranged supporting brackets, tensioning devices on said brackets, the longitudinally extending members of the netting being held taut by helical springs, brackets which have lateral bends, the ends of said brackets movably coupled to supports on which the tensioning devices act, and adapted to hold the longitudinally extending members with their respective tensile springs by means of said supporting brackets at a uniform tension, the said brackets connected with tension nuts by means of looped slings, tension 20 springs and longitudinally extending members, said tension nuts screwing on screw spindles secured in a transverse beam of the frame, the free edges of the netting formed by cross webs with eye shaped lateral bands 25 of tension shackles and closed links connecting said shackles with each other the said closed edge links of the netting closed at their upwardly directed legs by means of wire loops and having bends into which the longitudinally extending members forming the netting are immovably engaged with interposed leather packings, the netting supported at its corners by supporting brackets forming simultaneously the corner of the 30 netting angular webs on said brackets, said webs, the corner and the ends of the adjoining edges being each connected to brackets held by pressure springs pivoted to the respective sides. 35
